UNITED STATES PATENT OFFICE.

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA.

HEAT-BALANCE CONDENSER PLANT.

Application filed October 30, 1926. Serial No. 145,199.

My invention relates to power plant condensing equipment and it has for its object to provide apparatus of this character which shall permit of improved thermodynamic performance, particularly where, for a given equipment, the ratio of make-up water is relatively large.

In power systems, where a part of the steam generated is used in process work, it is necessary to supply to the boilers make-up water sufficient to compensate for the amount of steam bled from the system. Such make-up water should, of course, be heated before entering the boilers and dissolved gases should be removed therefrom so far as is possible. Accordingly, therefore, I condense steam exhausted from the prime mover in part by a surface condenser, the remaining condensation being effected by a jet condenser receiving condensed and non-condensed media from the surface condenser and which is supplied with make-up water as the condensing medium. In this way, the make-up water is heated, and the incidental rise in temperature promotes separation of dissolved gases, the latter result being assisted by suitable air removal apparatus. More specifically, therefore, my invention has for an object to provide, in connection with a system where a relatively large ratio of make-up water to motive steam is required, condensing equipment including a surface condenser and a jet condenser arranged in series, the jet condenser being served with make-up water as its condensing medium, whereby the make-up water may be heated. A further object is to provide suitable air removal apparatus in connection with the jet condenser to assure the removal of air and non-condensable gases entrained or dissolved by the make-up water, separation of such air and gases being assisted by the heating taking place in the jet condenser.

Referring to the drawings wherein I show the preferred physical embodiments of my invention:

Fig. 1 is a transverse section of a straight, down-flow, surface condensing unit of the divided water box type embodying my invention;

Fig. 2 is a transverse section of a straight, down-flow, surface condensing unit of the non-divided water box type embodying my invention;

Fig. 3 is a transverse section of a semi-radial flow surface condensing unit of the non-divided water box type embodying my invention;

Fig. 4 is a transverse section of a radial flow type of surface condensing unit embodying my invention;

Fig. 5 is an end elevation of a form of my invention similar to Fig. 3, but showing a different type of controlling means;

Fig. 6 is an end view shown somewhat diagrammatically of my invention and the improved means for selectively removing air and non-condensable gases;

Fig. 7 is a side elevation of a surface condensing unit embodying my invention;

Fig. 8 is a fragmentary view showing a modified form of my control means;

Fig. 9 is a sectional view with parts removed showing a surface condensing unit embodying a modified form of my invention;

Fig. 10 is a section on the plane XX of Fig. 9;

Figs. 11 and 12 are further modifications of my control means, Fig. 11 showing the control means used in connection with a surge tank and adapted to regulate either the speed of the condenser feed pump or the discharge valve thereof, while Fig. 12 shows the control means adapted to operate a bypass valve.

In industrial plants where considerable steam is supplied from a prime mover after partial expansion for process work, or otherwise, a like amount plus that lost through leakage must be introduced into the system in the form of boiler feed make-up.

In many industrial processes this boiler feed make-up is a greater percentage of the station boiler capacity than main unit steam converted into power, and in such cases the problem of economic introduction of the same into the system is presented. For instance, in such a plant the steam finally passing to the main condenser may be 35,000 pounds, whereas the normal boiler feed make-

up may be 100,000 pounds per hour. Accordingly it is an object of my present invention to provide such an arrangement of condensing apparatus that the relatively 5 large amount of make-up feed water may be heated and air and non-condensable gases may be readily removed. In order to secure suitable heating and deaeration of the feed water, I provide a surface condenser of 10 such capacity that it does not effect complete condensation but discharges uncondensed steam into a jet condenser, the latter receiving, as its cooling medium, the make-up water. In this way, the make-up water is 15 heated; and the manner of its introduction and the step of heating, facilitate removal of air and non-condensable gases by suitable apparatus.

In Fig. 1, I show a surface condensing element 10, of the straight, down-flow, divided water box type, having a shell 11 and a steam inlet 12 adapted to be directly connected to the exhaust of a prime mover, as, for example, a turbine. The tube nest 13 20 preferably has a vertical lane 14 extending longitudinally through the nest and forming a direct passage from the inlet 12 to the condensate discharge opening 15 in the bottom of the shell.

As is well known by those skilled in this art, condensers are sometimes equipped with divided water boxes, which are usually so arranged that approximately half of the tubes of the nest may be cut out of the 25 circulating system for cleaning, repair, or the like, while the other tubes remain in service. The water boxes of a condenser of this type are ordinarily provided with similarly disposed partitions, which may be vertical, and each water box is provided with the necessary inlet or outlet connections so that there are in effect two separate and independent 30 circulating systems in a single shell and these systems may be in operation alternately, or simultaneously.

Obviously, where partitions occur in the water boxes, it is necessary to omit some tubes and to leave a blank space in the tube sheets opposite the partitions and hence, to leave a relatively narrow steam lane 35 through the tube nest. In Fig. 1, the space within the shell is more efficiently utilized by slightly enlarging such a steam lane, as the lane 14, and utilizing it for passing steam directly through the surface condenser.

Instead of the usual hotwell, I attach a jet condenser 16 to bottom of the shell, the mixing chamber 17 of the jet condenser being in direct communication with nest of tubes 13 of the surface condensing element 40 and being adapted to receive condensate from the latter through the opening 15 in the bottom of the shell.

Disposed about the wall of the chamber 17, are a number of openings or nozzles 18

which are adapted to introduce into the mixing chamber 17 a fluid from the compartment or passage 19 encompassing the chamber. The passage 19 is adapted to be connected with some suitable source of boiler feed make-up water through the connection 21 and valve 22. The cooling water from the surface condensing element may be utilized for this purpose if desired. 70

The lower walls of the chamber 17 converge in the form of a nozzle 23 within the enlarged portion or cylindrical chamber 24 of the condensate offtake 26. Air and vapors are vented from the chamber 24 through passages 27 leading from each side of the chamber 24 to the cooling compartments 28. The tubes enclosed within these compartments are isolated from the rest of the nest by any suitable means such as the longitudinally extending vertical wall members 29 and the plates 31 which are secured to the upper flanged ends of members 29 and to the shell at some convenient location just above the offtake ports 32. 75

To prevent the accumulation of condensate in the compartments 28 a number of openings 32' inclined upwardly from the compartment side are located in the vertical walls 29 adjacent the shell, thus providing 80 water sealed drains for the compartments 28. 85

A chamber 33 communicates with the chamber 24 at any convenient point below the nozzle 23 and contains a float 34 carrying an actuating arm 36 adapted to actuate the valve 22 through a suitable relay, shown 90 diagrammatically at 37, the latter being connected by a link 37' to the valve 22. 95

The operation of the device shown in Fig. 1 is as follows: The exhaust steam enters through the inlet 12 and permeates through the nest where it is partially condensed, condensate and non-condensed media passing to the jet condenser 16. Boiler feed make-up water passes through valve 22 to passage 19 from which it is sprayed into mixing chamber 17 by the nozzles 18. Steam also passes 100 from the inlet 12 through the steam lane 14 directly to the mixing chamber 17 where condensation takes place and the make-up water is heated. 110

To insure the proper distribution of loading, or condensing effort, the boiler feed make-up is controlled depending upon the demand. This is accomplished by means of the float 34 acting through the relay 37 to 115 actuate the jet condenser injection valve either mechanically or electrically and thus reducing or increasing injection water according to the demand.

Condensate is removed from the chamber 125 24 by any suitable means, for example, by a pump 38.

In Figs. 2 to 5, inclusive, I show my invention embodied in surface condensing units of different types than that disclosed in Fig. 130

1; and in these figures the same reference characters have been used to indicate similar parts.

In Fig. 2, I show a non-divided water box 5 type of straight, down-flow surface condenser in which the steam lane 14 shown in Fig. 1, is omitted and a more liberal pitching of condenser tubes is employed to provide for the passage of the proper amount of 10 steam direct to the jet condenser. In this type, I also employ an isolated cooler section 28 for the air and noncondensable vapors; and, while I have shown only one such section, it will be obvious that two could be 15 employed in the manner shown in Fig. 1.

In Fig. 3, I show a semi-radial flow, non-divided water box type of surface condensing element in which a steam lane 14' is provided around one side of the tube nest. The 20 cooler section for the air and vapors is not isolated completely from the rest of the nest, entrance means 31' being provided for the passage of air and non-condensable gases directly from the surface condenser to the 25 cooler section.

In Fig. 4, I show a radial flow type of surface condensing element, in which the nest of tubes 51 is eccentrically disposed with respect to the shell, and which has the usual 30 air offtake 52 within the core of the nest, said offtake being protected by the rain plate 53. The air and vapors from the jet condenser are vented directly by conduit 27" to the core of the tube nest 51 from which they 35 are removed by the offtake 52.

While, in the views already referred to, I have shown a described means responsive to the level of water in the jet condenser to control the inlet of make-up feed water to the jet condenser, such water serving in the latter apparatus as cooling water, in Fig. 5, I show a series arrangement of surface and jet condensers wherein no control is exercised upon the circulating water, any variation in demand for feed water being taken care of by an overflow by-pass. In this view, I show the float mechanism, such as already described, connected to a valve 59 in the overflow discharge line 61. In case 45 of low demand for make-up feed water, a considerable part of the water discharged from the condensate removal pump 38 may pass out through the overflow conduit 61, the valve 59 being opened in response to the 50 liquid level in the jet condenser to allow for this. With increase in demand for feed water, the valve 59 would be moved toward its seat and more water would be supplied to the boiler. In case of maximum demand for 55 feed water, the valve 59 would be closed.

In Fig. 6, I show an arrangement whereby the surface condenser may be shut down for cleaning and the jet condenser depended upon for full duty of condensation in the 60 meantime. In this figure, in normal opera-

tion, air and vapors are removed from the jet condenser through the conduit 62, the valve 63 being closed and the valves 64 and 64' being open, said air and vapors going to the interior of the tube nest and from the latter they are removed through the conduit 65, valve 64' being open, to any suitable air removal means, such as an air ejector 66. When it is desired to shut down the surface condensing element the valves 64 and 64' are 70 closed and the valve 63 is opened and the air is removed directly from the jet condenser to the air removal means 66. The circulating media for the surface condenser is then shut off so that the tubes may be 75 cleaned, or otherwise repaired, without interfering with the flow of steam through the surface condenser to the jet condenser.

Reduction of injection water will reduce the condensing effort of the jet condenser 80 and thus cause a drop in vacuum unless the surface condenser is arranged to effect the additional condensation. On the other hand, increasing the injection of cooling water to the jet condenser makes possible 85 greater condensing effort by that condenser, thus reducing the demand upon the surface condenser. In the forms of my invention already referred to, I show controlling means only associated with the jet condenser, 90 the purpose in general, being to control the rate of supplying cooling water to the jet condenser in proportion to the liquid level existing in the lower portion of the jet condenser. While these arrangements make 95 possible regulation of the condensing effort of the jet condenser in proportion to the demand for make-up feed water, nevertheless, it may be desirable to regulate the flow 100 of circulating or cooling water in the surface condenser. For example, if the rate of supplying cooling water to the jet condenser is reduced, this immediately diminishes its condensing capacity, thereby resulting 105 in possible failure of the installation to effect complete condensation unless the surface condenser may effect additional condensation in proportion to the diminished capacity of the jet condenser. This is a matter of importance where considerable 110 variation exists in the requirements for process steam, it being desirable, of course, that the make-up feed water shall be heated in the jet condenser; and, in order that the latter result may be achieved, it is necessary 115 that the surface condenser shall pass sufficient steam to the jet condenser to effect the desired amount of heating of the make-up feed water.

In Figs. 7 and 8, I show arrangements 120 whereby, not only is the supply of make-up feed water to the jet condenser varied in the manner heretofore pointed out, but also the float mechanism serves to control the rate 125 of passage of circulating or cooling water 130

through the surface condenser. For example, in the operation of this type of apparatus, a diminution in the rate of supplying feed water to the jet condenser is accompanied by an increase in the rate of passage of circulating or cooling water through the surface condenser in order that the diminished condensing capacity of the jet condenser may be compensated for by increased condensing capacity of the surface condenser. In Fig. 7, I show a float arrangement having a float actuated relay 37 connected to a valve 22 by a link 37' as already referred to. In this view, the link 37' is connected to one end of a lever 69 fulcrumed at 70, the other end of the lever 69 being connected through a linkage mechanism 71 to a controller 72 of the motor 73 of the circulating pump 74.

In Fig. 8, I show a different way of effecting a dual control. In this view, the link 37' is connected by a bell crank 75 to a link 76, which serves to operate the valve 77 to control the passage of circulating or cooling water from the circulating pump to the condenser.

In Figs. 7 and 8, the arrangements are such that a variation in the rate of supplying make-up feed water to the jet condenser is accompanied by a reciprocal variation in the rate of supplying cooling or condensing water to the surface condenser, this being done in order that any change in condensing capacity of the jet condenser may be compensated for by a change in condensing capacity of the surface condenser.

By the arrangement shown in Figs. 9 and 10, I am able to obtain a relatively high mixture temperature. Referring to Fig. 9 it will be noted that the condensate from the surface condenser is removed through a conduit 78 and that walls 79 provide a seal against the flow of the main body of the condensate of the surface condenser into the jet condenser. The condensate from the main condenser and water discharged from the jet condenser enter a common conduit 80 and pass to a suitable removal pump.

In Fig. 11, I show a storage tank 82 on the suction side of the condensate removal pump. This tank is provided with a float 83 which is connected to the cooling water inlet valve of the jet condenser for controlling the rate of supplying cooling water to the latter.

In Fig. 12, I show a tank 84 on the discharge side of the condensate removal pump 38. The tank is provided with float control means similar to that shown on Fig. 11 and for the same purpose.

It will thus be seen that I have produced a very efficient means for heating make-up feed water and one which is especially adapted for industrial plants where a considerable amount of steam is used for

process work. It will also be obvious to those skilled in the art that the same injection water may be circulated in both condensing elements, the water flow to each being controlled automatically depending upon turbine load and circulating water temperature. My invention may also be employed in central stations as a means of introducing total station boiler feed make-up into any one of the main units and thus obviating the necessity of introducing this boiler make-up, even in central station plants, in small amounts to the various main condensing units.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a power system requiring a relatively large quantity of boiler feed water, the combination of a plurality of steam condensers connected in series, one of said condensers being of the contact type, and means for utilizing make-up feed water as a cooling medium in the contact condenser, whereby a relatively large quantity of heated water is made available for boiler feed purposes.

2. In a power system requiring a relatively large quantity of boiler feed water, the combination of a plurality of steam condensers connected in series, the condenser last in the series being of the contact type, and means for utilizing make-up feed water as a cooling medium in the contact condenser, whereby a relatively large quantity of heated water, consisting of commingled condensate and make-up feed water, is made available for boiler feed purposes.

3. In a power system requiring a relatively large quantity of boiler feed water, the combination of a plurality of steam condensers connected in series, the condenser last in the series being of the contact type, means for conveying make-up feed water as a cooling medium to the contact condenser, and means for removing commingled condensate and make-up feed water from the contact condenser, whereby a relatively large quantity of heated water is made available for boiler feed purposes.

4. In a power system requiring a relatively large quantity of boiler feed water, the combination of a surface condenser for partially condensing a quantity of exhaust steam, a contact condenser for completing the condensing process, and means for utilizing make-up feed water as a cooling me-

dium in the contact condenser, whereby a relatively large quantity of heated water is made available for boiler feed purposes.

5. In a power system requiring a relatively large quantity of boiler feed water, the combination of a surface condenser and a contact condenser connected in series, means for conveying extraneous water as a cooling medium to the surface condenser, and means for conveying make-up feed water as a cooling medium to the contact condenser, whereby the jet condenser is utilized both as a heater and a condenser and whereby a relatively large quantity of heated water is made available for boiler feed purposes.

6. In a power system requiring a relatively large quantity of boiler feed water, the combination of a surface condenser, a contact condenser arranged to receive both condensate and uncondensed steam discharged from the surface condenser, means for conveying make-up feed water as a cooling medium to the jet condenser, and means for removing commingled condensate and heated make-up water from the jet condenser.

7. In a power system requiring a relatively large quantity of boiler feed water, the combination of a surface condenser, a jet condenser arranged to receive both condensate and uncondensed steam from the surface condenser, means for utilizing make-up feed water as a cooling medium in the jet condenser, means for removing from the jet condenser commingled condensate and heated make-up water, and means for venting off air and non-condensable gases from both condensers.

8. In a power system requiring a relatively large quantity of boiler feed water, the combination of a surface condenser, a jet condenser arranged to receive both condensate and uncondensed steam from the surface condenser, means for utilizing make-up feed water as a cooling medium in the jet condenser, means for removing from the jet condenser commingled condensate and heated make-up water, and means located in one of the condensers for venting off air and non-condensable gases from both condensers.

9. In a power system requiring a relatively large quantity of boiler feed water, the combination of a surface condenser, a jet condenser arranged to receive both condensate and uncondensed steam from the surface condenser, means for utilizing make-up feed water as a cooling medium in the jet condenser, means for removing from the jet condenser commingled condensate and heated make-up water, and means located in the surface condenser for venting off air and non-condensable gases from both condensers.

10. In a power system requiring a relatively large quantity of boiler feed water, the

combination of a surface condenser, a jet condenser arranged to receive both condensate and uncondensed steam from the surface condenser, means for utilizing make-up feed water as a cooling medium in the jet condenser, means for removing from the jet condenser commingled condensate and heated make-up water, means for venting off air and non-condensable gases from the jet condenser to the surface condenser, and outlet means for the air and non-condensable gases located in the surface condenser.

11. In a power system requiring a relatively large quantity of boiler feed water, the combination of a surface condenser, a jet condenser arranged to receive both condensate and uncondensed steam as well as air and non-condensable gases from the surface condenser, means for utilizing make-up feed water as a cooling medium in the jet condenser, a chamber for cooling the air and non-condensable gases, and means for conveying air and non-condensable gases from the jet condenser to said cooling chamber.

12. In a power system requiring a relatively large quantity of boiler feed water, the combination of a surface condenser, a jet condenser arranged to receive both condensate and uncondensed steam as well as air and non-condensable gases from the surface condenser, means for utilizing make-up feed water as a cooling medium in the jet condenser, a chamber embodied in the surface condenser for cooling the air and non-condensable gases, means for conveying air and non-condensable gases from the jet condenser to said cooling chamber, and air and non-condensable gas outlet means provided in the chamber.

13. In a power system requiring a relatively large quantity of boiler feed water, the combination of a plurality of steam condensers connected in series, one of said condensers being of the contact type, means for conveying make-up feed water as a cooling medium to the jet condenser, and means responsive to the quantity of commingled condensate and heated make-up feed water for controlling the supply of cooling medium to the jet condenser.

14. In a power system requiring a relatively large quantity of boiler feed water, the combination of a surface condenser and a jet condenser connected in series, means for conveying extraneous cooling water to the surface condenser, means for conveying make-up feed water as a cooling medium to the jet condenser, and means responsive to the quantity of commingled condensate and heated feed water derived from the jet condenser for controlling the supply of cooling water to the surface condenser.

15. In a power system requiring a relatively large quantity of boiler feed water, the combination of a surface condenser and

- 15 a jet condenser connected in series, means for conveying extraneous cooling water to the surface condenser, means for conveying make-up feed water as a cooling medium to the jet condenser, and means responsive to the quantity of commingled condensate and heated feed water derived from the jet condenser for controlling the supply of cooling water to the surface condenser and the supply of make-up feed water to the jet condenser.
- 20 16. In a power system requiring a relatively large quantity of boiler feed water, the combination of a surface condenser and a jet condenser connected in series, means for conveying extraneous cooling water to the surface condenser, means for conveying make-up feed water as a cooling medium to the jet condenser, and means responsive to the quantity of commingled condensate and heated feed water derived from the jet condenser for increasing the supply of cooling water to the surface condenser and for diminishing the supply of make-up water to the jet condenser and vice versa.
- 25 17. In a power system requiring a relatively large quantity of boiler feed water, the combination of a surface condenser and a jet condenser connected in series, means for conveying extraneous cooling water to the surface condenser, means for conveying make-up feed water as a cooling medium to the jet condenser, and means responsive to the quantity of commingled condensate and heated feed water derived from the jet condenser for increasing the supply of cooling water to the surface condenser and for diminishing the supply of make-up water to the jet condenser and vice versa.

In testimony whereof, I have hereunto subscribed my name this 30th day of September, 1926.

JOHN H. SMITH.
